UNITED STATES PATENT OFFICE.

JOSEPH A. GROEBLI, OF NEW YORK, N. Y., ASSIGNOR TO THE KURSHEEDT MANUFACTURING COMPANY, A CORPORATION OF NEW YORK.

EMBROIDERING-MACHINE.

No. 902,819.

Specification of Letters Patent.

Patented Nov. 8, 1908.

Application filed January 24, 1908. Serial No. 412,376.

To all whom it may concern:

Be it known that I, JOSEPH A. GROEBLI, a citizen of the United States, and a resident of the city, county, and State of New York, have invented certain new and useful Improvements in Embroidering-Machines, of which the following is a specification.

It is customary in embroidering machines to employ a double set of borers which pierce the fabric carried upon the tambour frame and consists of a set which is provided with cutting edges for cutting different shaped holes in the fabric where the design requires; and a second set of plain borers which merely pierce the finished or stitched hole to shape it, the latter sometimes being called stupfels. In such machines the various sets of borers are arranged in numbers along carrying bars and one set is adapted to be moved into operative position and operated while the other remains idle, and both of which remain out of operative position when not performing their functions. Heretofore such devices have been controlled by hand by an operator or have been controlled automatically by the jacquard and it is to the latter class of machines that my present invention belongs.

The objects of my improvements is to produce a more perfectly operated device which may be connected with an embroidering machine in a less cumbersome and more positive acting manner and which may be utilized upon machines to which former devices are not adapted.

The device comprises mechanism for connecting the actuating mechanism with either set of borers, means for operating the set thus connected and mechanism for withdrawing the borers from their operative position, all of which are automatically controlled by the pattern device.

The various details of one embodiment of my invention, and the advantages thereof will appear more fully hereinafter.

In the drawings forming a part of this application, Figure 1 is a front elevation of a portion of an embroidering machine showing my improved mechanism, Fig. 2 is a side elevation thereof, Fig. 3 is an enlarged view of a portion of Fig. 2, showing the parts in a different position, Fig. 4 is a plan view, Fig. 5 is an enlarged side elevation of portions of the mechanism, Figs. 6 and 7 are an eleva-

tion and plan view respectively of the shaft 55 operating and positioning lever, Fig. 8 is a cross section taken on the line 8—8 of Fig. 7 and partly broken away, Fig. 9 is an elevation of a gear and cam for operating the mechanism, Fig. 10 is a cross section taken 60 on the line 10—10 of Fig. 9, Fig. 11 is a cross section taken on the line 11—11 of Fig. 10, and Fig. 12 is a cross section taken on the line 12—12 of Fig. 2.

By reference to Figs. 1 and 4 it will be seen 65 that there are two sets of borers 1 and 2 which are mounted on rods 3 and 4 respectively that extend lengthwise of the embroidery machine, and in the form of the machine to which my invention is best adapted these 70 sets of borers are arranged one above the other and below the needles, where, when they are moved into operative position they will not be liable to injure the hands of the operator while attending to the threads. 75 These two borer rods are connected upon lateral shafts 5 and 6 which move longitudinally in journals 7 for the purpose of moving the borers in and out for the purpose of boring the fabric wherever the design requires. 80 The shafts 5 and 6 are duplicated at the opposite end of the machine and at various intermediate points so as to make the movement of the borer rods uniform throughout. 85 The shafts may have oil grooves as shown. 90 For the purpose of directly operating the several shafts 5 and 6 I provide shafts 8 which are mounted in suitable bearings and extend longitudinally of the machine near the outer ends of the shafts 5 and 6. The shafts 5 and 90 6 are each provided with engaging members, 9 and 10 secured thereto, and each of the latter is provided with two fingers 11 and 12 projecting laterally of the shafts 5 and 6 and the fingers 12 are slightly longer than the fingers 11 for the purpose which will appear hereafter. The shafts 8 are provided with a plurality of cranks for reciprocating the shafts 5 and 6 to operate either set of borers. 95 The crank 13 has a roller 14 which moves into engagement with the arms on the member 9 while the oppositely disposed roller 16 on the crank 15 moves into engagement with the fingers on the member 10. When the shaft 8 is in the position shown in Fig. 4 the crank 100 13 reciprocates the shaft 5 and with it the upper set of borers and the crank 15 moves idly back and forth and as it only engages with

the finger 12 it keeps the shaft 6 and lower set of borers out of operative position. When the shaft 8 is moved longitudinally by mechanism to be explained, the roller 14 will 5 cease to operate the shaft 5 and the roller 16 will be moved into engagement with the finger 11 when the shaft 6 and lower set of borers will be reciprocated while the upper ones remain idle and out of operative position. 10 The shifting of shaft 8 as well as other actions are all controlled by the pattern mechanism as will appear.

Referring now to the mechanism connected directly with the jacquard for the 15 purpose of operating the various movements, it will be seen that some of the parts are similar to that shown in my Letters Patent No. 717843. A shaft 17 is provided with a small gear 18 which meshes with gear 20 19 to which an arm 20 is fulcrumed to move when gear 19 rotates. Surrounding the shaft 17 (see Figs. 10 and 11) is a reciprocating member 21 which carries oppositely disposed gear teeth 22 and 23 for the 25 purpose of mutilating the gear 19 alternately on opposite sides. An arm 24 upon the lever 25 which rocks at 26, engages the reciprocating member 21 when the latter is in its raised position, to lock the gear 19 from rotating and when the mutilating member 30 moves to its lower position shown in Fig. 11 it will be free to pass the arm 24 and as the second arm 27 will be rocked by a spring and operate an alarm to signify that the borers 35 are being placed into operative position, the same as in my issued patent referred to. The reciprocation of the mutilating member 21 is controlled by an arm 29 operated by the jacquard, which engages a pin 30 on the 40 mutilating member the same as in my prior patent. The jacquard and the way in which it operates the arm 29 is fully illustrated and described in Patent No. 717843 to which cross reference is here made. When 45 the mutilating member is thrown into its lower position shown in Fig. 11 it will set the gears 18 and 19 into engagement when the latter will be revolved one half revolution when the opposite mutilation will 50 bring the gear to a stop until a repeated operation of the mutilating member. Similar to my prior patent there is a cam 31 which will rock the lever 32 when the roller 34 is thrown into engagement with the cam 55 by the jacquard, and rock the rod 33 which has an adjustable connection 35 with the lever 32.

By means of the rods 20 and 33 the setting of the borers into operative position and 60 their action is controlled as will now appear. The upper end of the rod 20 is fulcrumed to a crank 36 upon a shaft 37 whereby the rocking of shaft 37 by the rod 20 will rock a crank 38 on the opposite end. The crank 65 38 is provided with a reversely curved an-

nular cam 39 which serves a double purpose. It might be noted here that the borers and operating shaft 8 are duplicated as is customary on embroidering machines, one set being above the other the same as the 70 needles. A vertically disposed connecting rod 40 is connected at its opposite ends to levers 41 on short shafts 42, and on these short shafts are cranks 43 which straddle the shafts 8 between collars 44 on the latter 75 and when the cranks 43 are rocked the shafts 8 will be simultaneously reciprocated in either direction for the purpose of throwing one set of borers into action and the other out. 80

The connecting rod 40 is provided with an arm 45 on which there is a pin 46 that moves in the annular cam 39 and through this connection the rod 40 is moved vertically to set the shafts 8. Owing to the shape of the 85 annular cam the rod 40 is locked in its respective positions. A bell crank lever which rocks on the shaft 47 has an upward arm 48, provided with a pin 50 that also moves in the annular cam and an arm 49 which is 90 fulcrumed to a rod 51.

A vertically disposed reciprocating member 52 is connected so as to simultaneously rock the shafts 8 to operate the borers. This member 52 is provided with two corresponding racks 53 (upper and lower) which mesh with sectors 54 on the ends of the shafts 8, so that as the member 52 moves up and down the shafts 8 will be rocked a portion of a revolution through this rack and pinion 95 movement. The member 52 is itself operated through the action of the rod 33. As one set of borers is provided with cutting edges they must be sharpened from time to time and doing so the length of the borers 100 is decreased, so that the shafts 8 must be so adjusted that when the borers which have become shortened are operated their bar must be thrown farther in, in order to properly bore the fabric and still not change the 105 remaining borers which do not change to any appreciable extent in length. This adjustability is provided for in the connection between the rod 33 and reciprocating member 52; and is as follows: A shaft 55 is supported upon the frame of the machine by a bracket 56 and has a crank 57, which, by engagement in an aperture in the plate 57 on the member 52 reciprocates the latter when the shaft 55 is rocked. There is a double 110 connection between the shaft 55 and operating rod 33 one of which is loose upon the shaft and the other fixed so that by changing the position of these connecting means with relation to each other, the extent of reciprocation of the member 52 and through its connections the reciprocation of the borers may be advanced so as to make up for the decreased length of one set of borers. This 115 adjustment is such as to affect only one set 120 125 130

of borers and is such that when the normal or unshortened borers are thrown into operation the adjustment just referred to will be thrown out, and this change is effected 5 through a connection with the jacquard as will appear.

Reference is here had more particularly to Figs. 6, 7 and 8. A lever 59 is fulcrumed at 60 to a pin 61 running crosswise at the end of 10 the rod 33 and the opposite end 62 of this lever is U shaped and loosely sleeved upon the shaft 55. A two pieced jointed lever 63, straddles the lever 59 and is fulcrumed there- 15 to upon a pin 64, with one end 65 outside and the other inside. The end 65 is rocked by 20 the arm 51, the connections of which have already been described. Another lever 66 is fast upon the shaft 55 and runs generally parallel with the lever 59. Means are pro- 25 vided whereby the rocking of lever 63 will set or alter the position of lever 66 and through the various connections, the shafts 8. The end 67 of lever 63 is provided with teeth 68 which mesh with teeth 69 on a rock- 30 ing member 70 which rocks upon the pin 61 of the rod 33. This member 70 which I will preferably call a locking cam, is provided with a circular faced outer end 71 and pro- 35 jections 72. The lever 66 is provided with lateral extensions 73. On the upper one 40 there is a stationary cam toe 74 having a slanting inner surface 75, and a recess 76 at the bottom of the cam toe to receive one of the projections 72. Another toe 77 is se- 45 cured to the other projection 73 in a reverse position and is similar to the first one except that it is adjustable on the extension 73, by means of the slot 78 and screw 79 connec- 50 tion. When the cam toes are in the position shown in Fig. 8 the rocking of lever 63 and the connected parts will cause no change in the position of the lever 66. If, however, 55 the cam toe 77 is moved toward the lever 66 through its adjustable connection, the swing- 60 ing of the cam block 70 will cause the surface 71 thereof to engage the inclined surface 75 of cam toe 77, previous to what it would have and will rock the lever 66 downwardly in relation to the lever 59, and through its connec- 65 tions will move the member 52 upwardly and finally turn the shafts 8. When the lever 66 is thus adjusted the movement of the arm 33 will be the same in extent as before so that the rocking of shaft 55 and the recip- 70 rocation of one set of borers will be the same distance as before but the borer rod will start from another, or advanced position. When the lever 63 is rocked in the reverse direction the cam 70 will be thrown over and 75 upon engaging with the cam toe 74 will return the lever 66 to its former position. At each alternate swinging of the cam lock the one set of borers is advanced to make up for their shortening due to the sharpening. As 80 was explained one set of borers does not

change in length so that the lever 66 is re- 85 turned to its normal position when such set of borers is being operated. As will be seen, the projections 72 engage in the recesses 76 in either position of the cam lock, thus locking the rod 33 and lever 66 and making them move together. One of the most important features of this connection is that the shifting of the position of the lever 66 is effected 90 automatically whenever the power is shifted from one set of borers to the other.

Having described the details of construction of my improved device I will now describe their operation, beginning with the action of the jacquard. The arm 29 is moved 95 down by the action of the jacquard, carrying the pin 30 and the mutilating member, until the teeth engage the gear 18 when the latter will revolve the gear 19 until the opposite mutilated side of the gear 19 comes opposite 100 the gear 18 when the latter will continue to move idly. The half revolution of the gear 19 moves the rod 20 upwardly, causing the shaft 37 and crank 38 to rock. This will move the connecting rod 40 downwardly by 105 reason of the connection of the latter through the annular cam, when the levers 41 will be rocked. This causes the shafts 42 to rock to the left (Fig. 2) moving the shafts 8 longitudinally until the roller 16 engages the fingers 11, when the roller 14 will be free of the finger 11 on the shaft 5. When the shafts 8 are rocked in this new position the lower set 110 of borers will be operated instead of the upper. The movement of the annular cam 39 also rocks the bellcrank lever through the engagement of the arm 48 therewith, causing the rod 51 to move downwardly and rock the lever 63. This will turn the cam lock 70 and throw it into the position shown in Figs. 6 115 and 8. If the cam toe 77 is the same distance from the center of lever 66 as the toe 74 there will be no change in the position of lever 66. If, however, it is nearer, then the lever 66 will be moved downwardly and shaft 55 will 120 be turned slightly before the rod 33 begins to operate and through the connections the member 52 will be slightly raised and the rack and pinion engagements with shafts 8 will partly rock the latter and cause whichever set of borers is in operation (in the present description the upper) to be advanced to make up for the decreased length of the cutting borers. When the cam lock has been 125 moved as just described, the end 72 will engage in recess 76 on the lower cam shoe and cause the lever 66 to rock with the rod 33. The parts are now set for action. The pin 34 will now be thrown into the cam 31 by the action of the jacquard when the lever 32 will rock, moving the rod 33 up and down. This will cause the lever 66 to rock shaft 55, the crank 57 to reciprocate the member 52 and through the rack and pinion connection, the 130 shafts 8, to operate the borers. This will

continue until the pin 34 is withdrawn from the cam 31, which will be at the position shown in Fig. 1. The mechanism by which the bowl or pin 34 is thrown into and out of engagement with the cam 31 is fully illustrated and described in my pending application numbered 358736, filed February 21st, 1907, to which cross reference is made. The next operation may require that the upper 10 borers be used, and in this event the lever 29 will be moved downwardly by the jacquard as before and the mutilating member on the gear 19 will be reciprocated as before and the gears 18 and 19 will engage and the latter 15 will be revolved a half revolution. As the rod 20 was left at the top position on gear 19 in its previous action it will now move downwardly and move shaft 37 in a reverse direction to the previous movement. This will 20 reverse the position of the connecting rod 40 and through the various connections the shafts 8 will be moved longitudinally and reverse the connections of the cranks 13 and 15 to throw in the set of borers which were 25 previously idle. At the same time the bell-crank lever will be rocked by the annular cam, and through the rod 51 and lever 63 the locking cam 70 will be rocked into engagement with the cam toe 74 and the lever 66 30 will be returned to its previous position and the borers will be in their proper positions. The rocking of the rod 33, lever 66 and reciprocation of member 52 then begins as before 35 and the set of borers which were previously idle are operated.

It will be obvious from the foregoing that the setting of either set of borers into operative position is directly controlled by the jacquard, adjustment of the borers for decrease in their length is provided for, and the operation of the borers is controlled through the jacquard, so as to be operated after the borers are set. This is also accomplished in a way that insures positive and automatic 45 action with as few parts as possible and without adding clumsy parts to an already complicated machine.

The shifting of the borer operating shaft to alternately throw the different sets of borers 50 into action effects the necessary change in a very simple way without depreciating the positiveness of the operating parts.

My invention I deem to be broadly new in many of its features and I therefore do not 55 wish to be limited to specific details except where such details are set forth in the claims.

Having described my invention what I claim is:

1. An embroidering machine embodying a 60 plurality of sets of borers, a longitudinal operating shaft adapted to operate the borers, means whereby the reciprocation of said shaft will set it into operative connection with either of said sets of borers, pattern mechan-

ism and means controlled by the pattern 65 mechanism and adapted to reciprocate said operating shaft.

2. An embroidering machine embodying a pattern mechanism, a plurality of sets of borers, a longitudinal operating shaft adapted to 70 operate the borers, means whereby the reciprocation of said shaft will set it into operative connection with either of said sets of borers and means whereby the pattern mechanism will reciprocate said shaft and lock it in its 75 several positions.

3. An embroidering machine embodying a pattern mechanism, a plurality of sets of borers, a longitudinally reciprocating shaft, and means whereby the rocking of said shaft will 80 operate the borers, means for rocking said shaft, means whereby the reciprocation of said shaft will set it into operative connection with either set of borers, and means controlled by the pattern mechanism, for reciprocating 85 said shaft.

4. An embroidering machine embodying a pattern mechanism, a plurality of sets of borers, a longitudinal shaft, means whereby the rocking of said shaft will operate the borers, 90 means whereby the reciprocation of said shaft will set it into operative connection with either set of borers, means for rocking said shaft and means for reciprocating the shaft, the said rocking and reciprocating means being 95 separately controlled by the pattern mechanism.

5. An embroidering machine embodying a pattern mechanism, a plurality of sets of borers, lateral shafts for moving said borers, a 100 longitudinal shaft adapted to be reciprocated and provided with cranks which are adapted to operate said borer shafts, means whereby the several cranks will be thrown into operative connection with either set of said borer 105 shafts, upon the reciprocation of said longitudinal shaft and means controlled by the pattern mechanism for reciprocating the latter shaft.

6. An embroidering machine embodying a 110 pattern mechanism, a plurality of sets of borers, lateral shafts for moving said borers, provided with laterally projecting fingers of different lengths, a longitudinal shaft having cranks provided with pins which will engage 115 said lateral fingers on the borer shafts and means for reciprocating said longitudinal shaft to cause the pins on the said cranks to engage the said lateral fingers on the borer shafts for the purpose of setting either of said 120 borer shafts into operation, and means controlled by a pattern mechanism for rocking said longitudinal shaft.

7. An embroidering machine embodying a 125 pattern mechanism, a plurality of sets of borers, a longitudinal shaft adapted to operate the borers, means whereby the reciprocation of the said shaft will place it into operative

connection with either set of borers, means for reciprocating said shaft, a reciprocating member connected to said shaft by a rack and pinion engagement whereby it will rock the 5 shaft and operate the borers, and means controlled by the pattern mechanism for operating said reciprocating member.

8. An embroidering machine embodying a pattern mechanism, an upper and lower set 10 of borers, each of which embodies a double set of borers, longitudinal shafts for operating said borers and adapted when moved longitudinally to be set into operative engagement with either of said last mentioned sets of borers, a plurality of levers adapted to reciprocate said shafts, a connecting rod between 15 said levers, and means controlled by the pattern mechanism adapted to operate said rod, comprising a reverse annular cam connected 20 with said rod.

9. An embroidering machine embodying a plurality of sets of borers, a longitudinal shaft adapted to operate said borers, and to be placed into operative position with either set 25 of borers, means for rocking said shaft for operating the borers comprising in its construction an arm connected with a source of power, a shaft and a plurality of levers connecting the said arm and shaft, one of which 30 is fixed to the shaft and the other loose thereon and means for adjusting the position of said fixed lever to change the operative position of said borers.

10. An embroidering machine embodying a 35 plurality of sets of borers, a longitudinal shaft adapted to operate the borers and to be placed into operative engagement with either set of borers, and means for rocking said shaft for operating the borers comprising in its construction a shaft and a crank thereon, an operating arm connected with a source of power 40 and adapted to rock said last shaft and means for adjusting the connection of said arm and shaft to advance the position of a set of 45 borers.

11. An embroidering machine embodying a pattern mechanism, a plurality of sets of borers, a longitudinal shaft adapted to operate the borers and to be placed into operative engagement with either set of borers and means for rocking the said shaft for operating the said borers comprising in its construction a shaft and a crank thereon, an operating arm connected with a source of 50 power and adapted to rock said crank and means controlled by the pattern mechanism for adjusting the connection of said arm and crank to advance the operative position of a set of borers.

12. An embroidering machine embodying a pattern mechanism, a plurality of sets of borers, a longitudinal shaft adapted to operate the borers, and means for operating said shaft comprising in its construction a shaft,

and an arm connected with a source of power, 65 a plurality of connecting members, one of which is loosely sleeved on said shaft and connected to said arm, another secured to said shaft and adapted to be moved by the pattern mechanism with relation to said first member to alter the position of a set of borers, a plurality of cam toes on said fixed lever, one of which is adjustable, and a rocking cam adapted to engage with said toes, to alter the position of said fixed lever and advance the position of a set of borers. 70 75

13. An embroidering machine embodying a plurality of bore mechanisms, a single operating mechanism for the bore mechanisms, comprising in its construction a shaft, a compensating device through which the shaft is operated, consisting of a loose and a tight arm on said shaft, means adapted to alter the position of a bore mechanism through said arms and to lock the parts in their several 80 changed relations and means for transmitting power to said shaft through said arms. 85

14. An embroidering machine embodying a pattern device, a plurality of bore mechanisms, a single operating mechanism for the 90 bore mechanisms, comprising in its construction a shaft, a compensating device, consisting of a tight and a loose arm on said shaft, means adapted to alter the position of a bore mechanism through said arms, and to lock 95 the parts in their several relations, said means being controlled by the pattern device and means for transmitting power to said shaft through said arms.

15. An embroidering machine embodying 100 a plurality of sets of bore mechanisms, a pattern device, a single operating mechanism for both bore mechanisms, including an operating shaft, means controlled by the pattern device for connecting the operating 105 mechanism with either set of bore mechanisms and means for rotating said shaft a variable extent to compensate for inequalities between the bore mechanisms.

16. An embroidering machine embodying 110 two sets of bore mechanisms and a single operating mechanism therefor, and compensating mechanism for imparting an auxiliary movement to the operating mechanism comprising in its construction a shaft, a tight and 115 a loose arm on the shaft connected by means which are adapted to interlock, one of said latter means being adjustable for the purpose of altering the operating mechanism.

17. An embroidering machine embodying 120 a pattern mechanism, two bore mechanisms and a single operating mechanism therefor, comprising in its construction a shaft having a loose arm and a fixed arm, a member carried by the loose arm and members carried 125 by said fixed arm with which the said member on the loose arm engages and with which it interlocks and mechanism controlled by

the pattern mechanism adapted to cause the loose arm member to engage with one or the other of said fixed arm engaging members for the purpose of producing an auxiliary 5 movement of the operating shaft.

18. An embroidering machine embodying a pattern mechanism, a plurality of bore mechanisms, a single operating mechanism for the bore mechanisms, comprising in its 10 construction several power applying mem-

bers, and means controlled by the pattern mechanism adapted to advance the position of one of the power applying members, for the purpose of advancing a set of borers.

Signed this 22nd day of January, 1908. 15
